UNITED STATES PATENT OFFICE.

CLINTON C. BUTLER, OF POMONA, CALIFORNIA.

LOCK CHECK PIN.

Application filed March 2, 1928. Serial No. 258,597.

This invention aims to provide a simple but effective means whereby articles of laundry may be checked in such a way as to render confusion unlikely to occur, it being 5 possible to make a wide variety of combinations out of a very few elements, and those elements being of a simple sort.

It is within the province of the disclosure to improve generally and to enhance the 10 utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within 20 in the scope of what is claimed, without departing from the spirit of the invention.

In the drawings:—

Figure 1 shows in perspective, a device constructed in accordance with the invention; 25

Figure 2 is an elevation showing two checking devices constructed in accordance with the invention, and mounted on a panel or the like;

Figure 3 is a plan showing one of the check plates;

Figure 4 is a side elevation of the complete device depicted in Figure 1;

Figures 5 and 6 are plans showing modifications; and

Fig. 7 is a plan showing the check plate used with the form depicted in Fig. 6.

The device forming the subject matter of this application preferably is made of metal 40 and includes a support 1, in the form of a plate, having openings 2, adapted to receive screws 3 or other securing elements, whereby any desired number of supports 1 may be held on a panel 4 or anything else that is handy and adapted for the purpose in view. In each support 1 are fixedly mounted any desired number of approximately parallel pins 5, there being two pins on each support 1 in the embodiment of the invention 45 selected for illustration. The pins 5 may be tapered at their ends, as shown at 6, so that the check plates 7 (hereinafter described in detail) may the more readily be mounted upon them. The pins 5 are supplied near to

55 their free ends with laterally projecting wings 8 which are located at different angles

with respect to a plane A—B passing through the axes of both of the pins 5.

For each pair of pins 5 there is provided a check plate 7, the plate being supplied with transversely spaced openings 9 adapted to receive the pins 5 closely, the plate being equipped with slots 10 which communicate with the openings 9, the slots 10 being so shaped as to receive the wings 8 closely. 60 Comparing the right-hand and left-hand portions of Figure 2, it will be seen that the pins 5 may be set in the support 1 with the wings 8 in any desired angular relation with respect to the plane A—B, and in this way, 65 a large number of combinations may be made, there being one of the check plates 7 for each pair of pins 5, and the slots 10 in the check plate being located to correspond with the angular position of the wings 8. 70 The result is that, through the use of few elements, and those elements of a very simple kind, almost endless number of different check plates may be provided. 75

In Figure 5 of the drawings, a modification of the invention has been shown. The modification consists in this: that one of the wings, marked specifically by the numeral 11, is not disposed radially of the pin, as is the wing 8^a, and the corresponding wings 8^b of Figure 2. 80

In Figure 6 of the drawings, parts hereinbefore described have been designated by numerals previously used, with the suffix "b". The modification, in Figure 6, consists 90 in the fact that one of the wings 12 is made up of angularly disposed parts, whereas the wings 8^b, 11, 8^a and 8, have no angles in them. The check plate used in connection with the form shown in Figure 6 is disclosed in 95 Figure 7, and parts hereinbefore described have been designated by numerals previously used, with the suffix "c".

All of the check plates have reduced ends 14 provided with openings 15 adapted to 100 receive rings 16 or the like, connected to safety pins 17 or equivalent structures, the pins 17 being adapted to hold the articles which are to be classified and arranged.

What is claimed is:—

1. In a laundry-checking device, a support, a plurality of transversely spaced approximately parallel cylindrical pins projecting from the support, laterally extended wings on the pins, and a check having transversely spaced openings receiving the pins, the check being provided with slots which 110

communicate with the openings, the slots being so shaped as to receive the wings closely.

2. In a laundry-checking device, a support, a plurality of transversely spaced approximately parallel pins projecting from the support, laterally extended wings on the pins, the wing on one pin being shaped differently from the wing on another pin, the wings being located in different

places, circumferentially of their respective pins, and a check having transversely spaced openings receiving the pins, the check being provided with slots which communicate with the openings, the slots being so shaped as to receive the wings closely. 15

In testimony that I claim the foregoing as my own, I have hereto affixed my signature.

CLINTON C. BUTLER.
